EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

THREAD TENSION FOR AUTOMATICALLY THREADING LOOM SHUTTLES.

Application filed July 6, 1925. Serial No. 41,533.

To all whom it may concern:

Be it known that I, EDWARD A. CUNNIFF, a citizen of the United States, residing at Waltham, county of Middlesex, and State 5 of Massachusetts, have invented an Improvement in Thread Tensions for Automatically Threading Loom Shuttles, of which the following description, in connection with the accompanying drawings, is a 10 specification, like characters on the drawings representing like parts.

This invention relates to automatically threading loom shuttles and more particularly to tension means in such shuttles 15 for exerting tension upon the thread during weaving.

It is now the ordinary practice to provide automatically threading loom shuttles with tension means to insure proper delivery 20 of the weft or filling thread during weaving. Such tension means, however, when employed in automatically threading loom shuttles, must offer no obstruction to the automatic threading operation on the first 25 pick of the shuttle following replenishment, and should act upon the thread thereafter to insure that the weft or filling thread shall be laid straight in the shed. Such tension means should also be adapted to 30 cooperate properly with the particular character of thread in use without injury thereto; for instance, a shuttle tension which may be adapted for use in connection with one kind or character of filling may be al- 35 together unsuitable for another kind or character of filling. This is particularly observable in automatically threading shuttles wherein the weft or filling thread is of silk or worsted, which require a non- 40 abrasive action upon the thread, such as would not be liable to cause injury thereto.

One of the objects of the present invention, therefore, is to provide an automatically threading loom shuttle with a tension device which will not only not interfere with the automatic threading of the shuttle on the first pick following replenishment, but will be adapted for cooperation 45 with any kind or character of filling to insure proper tension upon the thread during weaving.

The invention and new combination of

parts will best be made clear from the following description and the accompanying 55 drawings of one good form thereof.

In the drawings:

Fig. 1 is a perspective view of one end of a shuttle provided with the present invention;

Fig. 2 is a longitudinal section at one side of the longitudinal axis of the shuttle; and

Fig. 3 is a cross-section on the line 3—3 of Fig. 2.

The shuttle body 1 may be of usual character, preferably formed of wood, in which is mounted the filling carrier or bobbin 2 on which the filling 3 is wound, such filling carrier or bobbin being held in the shuttle 70 by the usual bobbin holding jaws (not shown, since such bobbin holding jaws are now well understood). Below the bobbin chamber the shuttle is provided with an opening 4 through which the denuded filling carrier may be ejected on replenishment of filling.

The shuttle herein shown is especially adapted for use in connection with a weft or filling thread formed of silk, the delicate 80 nature of which requires a special character of tension means, and the invention will be described in this connection, although it is to be understood that it is not necessarily limited thereto, since the tension device is adapted for use in connection with any character or kind of filling employed in a filling replenishing shuttle.

Frontward of the bobbin chamber the wood of the shuttle is cut away to provide a 90 threading block receiving chamber 5 in which is mounted the threading block 6, preferably formed of metal and having a longitudinally extending thread passage 7. The threading block 6 is provided with a 95 thread director 8 having the end portion 9 extended laterally of the thread passage and underlying a guard 10, as shown, the construction being such that once the shuttle is preliminarily threaded, as on the first 100 pick following replenishment, it will not thereafter escape from the control of the threading block. Frontward of the threading block the wood of the shuttle is cut away as at 11 to provide a thread passage 105 leading to the side delivery eye 12. The

threading block thus far described may be of usual or any preferred construction, the essentials in this respect being that the threading block will permit automatic 5 threading of the shuttle on the first pick following replenishment and thereafter be fully threaded on the return pick of the shuttle.

The threading block 6 is provided with 10 an undercut portion 13 adjacent the bobbin chamber, and as shown, such undercut portion of the threading block has a rounded contour in which is mounted the thread tension device. In the present instance of the 15 invention, the threading block 6 has also a downwardly extending stud 14 into which is threaded the head screw 15, which may constitute one form of means for holding the threading block in the threading block 20 receiving chamber.

In the present instance of the invention, the longitudinally extending thread passage is provided with a top opening 16 through which the thread passes to the thread passage 25 on the first pick of the shuttle following replenishment, and the lower wall 17 of the thread passage has a bridge 18 over which the thread α passes on its way to the side delivery eye 12.

30 Extending transversely through the shuttle within the chambered portion 13 of the threading block is a bolt 19 having a threaded end portion 20 engaged within the internally threaded bushing 21 secured in 35 the shuttle body.

The bolt 19 has mounted thereon the disks 22 and 23 each of which is provided with a convex surface 24 placed face to face, as indicated in Fig. 3, the portion of the disks 40 below the convex portions 24 being preferably arranged to receive between them the weft or filling thread α when the shuttle is completely threaded. Between the disks 23 and the adjacent side wall of the shuttle is 45 a washer 25 against which the flat face of the disk 22 bears, and similarly the washer 26 is mounted on the bolt 19 and bears against the flat outer face of the disk 23. Interposed between the disk 26 and the head 50 27 of the bolt 19 is a spring 28 which acts through the washer 26 upon the disk 23 to hold the two disks in thread tensioning position, the amount of tension exerted on the 55 thread being regulated by adjustment of the bolt 19.

The bolt 19 and the disks 22 and 23 are disposed within the recessed chambered portion 13 below the top portion of the threading block, and the opening between the disks 60 22 and 23 is disposed laterally to one side of the opening 16 of the threading block, as indicated in Fig. 3, the construction being such that when the thread passes downwardly through the opening 16 leading to the thread passage, it will be deflected by

the convex walls 24 of the disk as it moves downwardly into its final position, as indicated in Fig. 3.

Where the filling in use is made of silk or worsted, for instance, the tensioning disks 70 22 and 23 will preferably be formed of porcelain to thereby exert no injurious action upon the filling, and as the filling is withdrawn from the bobbin the porcelain disks will exert tension upon the thread during 75 its movement through the longitudinally extending thread passage.

The top surface of the bolt 19 on which the thread normally rests when in final threaded position is above the horizontal 80 plane passed through the bridge 18, with the result that the filling thread α is deflected downwardly over the top of the bolt 19 on its way to the side delivery eye. The effect of this is that notwithstanding the rotative movement of the porcelain disks 22 and 23, there will be no tendency exerted by them to throw the filling thread upwardly out of engagement with or from between their contacting surfaces, but, on the contrary, the 90 downwardly deflected thread in the thread passage will remain in tensioning position between the convex faces of the disks during the entire weaving operation.

From the construction described it will 95 be apparent that the thread tensioning disks 22 and 23 are disposed below the top surface of the threading block in the chambered portion 13 thereof, and that the bolt 19 supports the filling thread leading from the bobbin 100 as it passes between the convex surfaces of the disks above the horizontal plane passed through the bridge 18 of the thread passage, with the result that the thread is normally held during the weaving operation in its 105 tensioning position between the disks.

What is claimed is:

1. In an automatically threading loom shuttle, the combination of a threading block having a longitudinally extending threading passage and an undercut chambered portion formed in the block adjacent the bobbin chamber, two disks within the undercut chambered portion of the threaded block 110 provided with convex surfaces arranged face to face below overlying portions of the block, and a threaded bolt passing transversely through the chambered portion of the threading block on which the disks are 115 mounted.

2. In an automatically threading loom shuttle, the combination of a threading block having a longitudinally extending thread passage and an undercut chambered 120 portion adjacent the bobbin chamber connecting with the thread passage, two disks in the chambered portion of the threading block having convex surfaces arranged face to face below and at one side of the top 125 entrance to the thread passage, a bolt ex- 130

- tending transversely of the undercut chambered portion of the block on which the disks are mounted, the upper surface of the bolt being above the lower wall of the longitudinally extending thread passage that the thread may be deflected downwardly in the thread passage on its way to the side delivery eye.
3. In an automatically threading loom shuttle, the combination of a threading block having a longitudinally extending threading passage and an undercut chambered portion formed in the block adjacent the bobbin chamber, two porcelain disks within the chambered portion of the threading block provided with convex surfaces arranged face to face below and at one side of the top entrance to the thread passage, and a threaded bolt passing transversely through the chambered portion of the threading block on which the disks are mounted.
4. In an automatically threading loom shuttle, the combination of a threading block having a longitudinally extending thread passage provided with a bridge at its forward end over which the thread passes to the side delivery eye, said threading block having an undercut chamber frontward of the bobbin chamber beneath the top opening of the thread passage, two convex porcelain disks within the undercut chamber underly-
ing portions of the block and at one side of the top entrance to the thread passage, a threaded bolt on which the disks are mounted with the convex surfaces face to face, and a spring acting upon one of the porcelain disks.
5. In an automatically threading loom shuttle, the combination of a threading block having a longitudinally extending thread passage provided with a bridge at its forward end over which the thread passes to the side delivery eye, said threading block having an undercut chamber formed in the block frontward of the bobbin chamber below overlying portions of the block forming the top opening of the thread passage, two convex porcelain disks within the undercut chamber, a threaded bolt on which the disks are mounted with the convex surfaces face to face, the upper surface of the bolt being above the horizontal plane passing through the bridge to deflect the thread downwardly on its way to the side delivery eye, and a spring acting upon one of the porcelain disks.

In testimony whereof, I have signed my name to this specification.

EDWARD A. CUNNIF. 55
